United States Patent Office.

CONRAD FRIEDRICH L. RISCH, OF HUNTINGBURG, INDIANA.

Letters Patent No. 77,324, dated April 28, 1868.

IMPROVEMENT IN HELIOMETERS.

The Schedule referred to in these Letters Patent and making part of the same.

TO ALL WHOM IT MAY CONCERN:

Be it known that I, CONRAD FRIEDRICH L. RISCH, of Huntingburg, in the county of Dubois, and State of Indiana, have invented a new and improved Heliometer; and I do hereby declare that the following is a full, clear, and exact description thereof, which will enable others skilled in the art to make and use the same, reference being had to the accompanying drawings, forming part of this specification.

Figure 1, Sheet I, represents a plan or top view of my invention.

Figure 2, Sheet I, is a front elevation of the same.

Figure 3, Sheet II, is an end view of the same.

Figure 4, Sheet II, is a view of the opposite end.

Figure 5, Sheet III, is a vertical central section of the same, the plane of section being indicated by the line $x\ x$, fig. 1.

Figure 6, Sheet III, is a horizontal sectional view of the same, the plane of section being indicated by the line $y\ y$, fig. 2.

Similar letters of reference indicate corresponding parts.

This invention relates to a new apparatus, which is a perfect sun-dial for all latitudes, and by which the time of the day can be ascertained with exactness, by minutes and seconds; also, the degree of latitude above which the sun stands perpendicular during any one day; also, the date and length of day, as well as the time of sunrise and sunset.

By its use, the reason for the variations in the length of days is made perfectly clear.

The difference in the time of day between any two places on the globe can also be accurately ascertained, as well as the position of the earth-axis in relation to the surface of the water, and the size of the angle formed by the axis on the water-line; also the angle formed by the rays of the sun, at noon of each day, upon the water-line or level.

If the apparatus is set at noon according to the date, the exact degree of latitude of the place where the apparatus stands can be ascertained by it.

The principle of finding the position of the gnomon of the sun-dial at any certain degree of latitude will be established by the use of this heliometer and the angle formed by it and the level dial.

The object of the invention is to bring within reach of persons of but ordinary intelligence and education the knowledge of the principles and the understanding of the observations above referred to.

The invention will be of special value in schools, as, by the use of this apparatus, scholars will, with proper guidance, easily and quickly understand some of the more important branches of geography.

For nautical schools, surveying parties, and for travellers, it will be of great importance, and especially for travellers in large plains or deserts, as they can, at noon of every day, ascertain the latitude.

A represents a frame, consisting of two upright end-pieces, fitted to a suitable bed-plate.

The frame can be made of wood or other suitable material, and of any suitable dimension.

Upon the bed-plate are fitted a compass, a , and level, b , as shown.

To the face of each of the supports is secured a semi-annular plate, c , which is divided into one hundred and eighty degrees, as shown in figs. 3 and 4.

A metal bar, B , which has its bearings in the end-pieces of the frame, is the centre, from which the arcs $c\ c$ are struck. Upon the bar B is mounted, between the uprights of the frame, and so as to revolve with the axis, a cube, C .

This cube represents the earth, flattened to the shape shown.

Those two surfaces, d and e , which are created by flattening the poles, are called the polar surfaces.

The pins f and g , which project respectively from the centres of the polar surfaces, represent the earth-axis.

The shadow of these gnomons, f and g , thrown upon the polar surfaces, describes thereon the hour-circle of the astronomical day; therefore the said surfaces are provided with dials, as shown in fig. 2.

Within each stationary dial, on each polar surface, is a revolving dial, h , turning around the earth-axis.

The inner edge of the stationary dial is, as shown in fig. 2, divided into three hundred and sixty degrees. Thus, by means of the central revolving dial and this inner edge of the stationary dial, the difference between the time of day of any two places on the globe may be indicated and ascertained.

The main lines on the stationary dials are carried over and around the edges of the cube, for the purpose of letting the instrument be used as a model for making a correct stationary sun-dial.

The figures on the dials upon the polar surfaces are carried in opposite directions, those on the north pole going from left to right, while on the south pole, *e. g.*, they go from right to left, as shown in fig. 2, which is the plan of the south polar surface.

The reason for this arrangement is the opposite course of the shadow of the gnomon on the southern and northern hemispheres.

Therefore, also, and because the sun does not shine upon the north pole during six months, and upon the south pole during the other six months, each polar surface of the cube C will answer as a sun-dial only for six months; *i. e.*, the north polar surface d from the twentieth day of March to the twenty-second day of September of each year for the northern hemisphere, and from September to March for the southern hemisphere, while the south polar surface e will be correct from March to September for the southern, and from September to March for the northern hemisphere.

But, as it is inconvenient to inspect the winter side while the heliometer is set for any position of the globe between the forty-fifth degree of latitude and the pole, and to thus find the correct time, a semi-cylindrical depression, D, is arranged on the south side of the cube, which is always pointed towards the sun; and within the same is arranged a dial, as shown in figs. 1 and 5, and the shadow of a gnomon, i , indicates the time of day.

This semi-cylindrical dial is also most convenient during the equinoxes.

On the east side of the cube is arranged a triangular board or plate, E, which is also secured to the axis B, so as to turn with the cube.

The shorter lower side of this triangle is made in form of an arc, which is struck from the opposite vertex, the radius being double the length of the radius of the semi-annular index e .

The angle between the straight sides measures forty-seven degrees, and the lower arc is, consequently, considerably flatter than the arc e , as is clearly shown in fig. 3.

From the point j , the whole triangle D is divided into two equal parts by a line, which is marked the equator in fig. 3.

The arc at the bottom end of the triangle is divided, from each side of the equator, into twenty-three and a half degrees, as shown; and thus the whole arc represents a portion of a meridian, drawn through the equator, and extending from the northern to the southern tropic.

The lines at the sides of the triangle, therefore, form the tropics, as indicated.

The equator is prolonged beyond the arc by means of a pointer, K, as shown, which reaches upon the arc e , and by which the instrument can be set to any degree of the northern or southern latitude, as will be understood from fig. 3.

Between the arc of the plate E and the arc e is interposed a small block, l , which is attached to the triangle E, and has an outer edge corresponding to the shape of the arc e .

The length of the arc on l , on each side of the equator, is equal to thirty-one degrees on e , which have been divided into thirty parts, so that each degree on l is equal to one and one-thirtieth degree on e .

The object of this division of the arc l is to allow the instrument to be set with greater exactness, according to degrees and minutes.

The triangular plate E is surrounded by sheet-metal flanges, projecting towards the front, as shown. At the junction of these flanges, in the vertex of the triangle, a small hole or slot is cut through this flange, as indicated at m in fig. 3.

When the instrument has been set, according to compass and level, for the required degree of latitude, (39° north latitude, fig. 3) a ray of the sun, falling, through the slot or hole m , upon the arc at the bottom of the triangle, falls upon and indicates that degree of latitude (between the tropics) above which the sun stands perpendicular.

The same ray also shows the date of the month, as near as it can be shown in an instrument of ordinary size, a division indicating the dates, being arranged, for that purpose, upon the arc of the triangle, as shown in fig. 3.

The very exact date can be ascertained, with a small instrument, by a small table, in which the date is noted at which the sun stands perpendicular above any one particular degree between the tropics.

If the latitude is not known, and to be ascertained, the cube is turned at twelve o'clock at noon, so that the ray, through m , falls upon the date, when the latitude above which the sun is perpendicular is, at the same time, also indicated by the same ray, and the pointer K indicates, upon the arc e , the degree of latitude at which the observation is being made.

The instrument is then also set correct for the sun-dial.

F is a wooden or other plate, having two edges or sides straight, and parallel to each other, while the other two are curves, arcs of a circle, struck from the centre of the plate, as shown in fig. 4. This plate F is secured to the west side of the cube C, so as to turn with the same, the axle B being its centre, the radius of the curves at its two ends being equal to the radius of the arc e at the same end, so that the curves on e and F correspond with each other, as is clearly shown in fig. 4.

The arcs on plate F are divided into forty-seven degrees, twenty-three and a half on each side of the equator o , the equator o being parallel with the straight sides of the plate F, and passing through the centre of the plate, as shown.

The outer lines of the twenty-three and a half degrees represent the tropics, and the whole space between represents the torrid zone of the globe, or, rather, actually, but half a zone. The other half must be thought to be on the opposite side of the plate.

The lines between the tropics represent the degrees of latitude, which are, one after the other, crossed by the vertical rays of the sun.

The space between the centre of the plate and its curved ends is divided into six main divisions, indicating the six hours of the solar day, or, rather, the hour-lines, which divide the whole globe into twenty-four parts. Twelve such parts are shown on the plate F. The other twelve must be imagined on the back of the plate.

These twelve lines are formed as arcs of circles, struck from the centre, B, as shown.

They may be subdivided into half hours, quarters, minutes, seconds, &c.

These lines also indicate the meridians crossed by the sun after each hour of the day.

n is a fine wire or string, drawn from *o* to *o* on the arc *c*, across the plate F. This wire shows, on the zone, the true division-line between night and day.

Above, it is day, (including the back of the plate, *i. e.*, the whole hemisphere above the wire;) below, it is night.

The blue lines, shown in fig. 4, and drawn from the divisions at the arcs of the plate F towards the centre of the same, indicate the size of the angle which, at twelve, noon, the rays of the sun form with each level or water-line at each degree of latitude.

For example, in the drawing, the instrument is set with the plate E for the thirty-ninth degree northern latitude.

The equator on the zone on F falls upon degree fifty-one and a half on the arc *c*, (fig. 4.) The line (blue) which is drawn from the end, *P*, of the northern tropic diagonally through the centre, B, to the end of the southern tropic, shows, upon the arc *c*, 75° , while the (blue) line drawn from the end, *q*, of the southern tropic diagonally through the centre, B, to the end of the northern tropic, shows 28° upon the arc *c*.

Thus, on the thirty-ninth degree of northern latitude, the angle of the sun at noon upon the water-line is as follows: On the twentieth day of March, and twenty-third day of September, $51\frac{1}{2}^\circ$; on the twenty-second day of December, 28° ; on the twenty-first day of June, 75° , &c.

The other blue lines show the size of the angles during the other days of the year from that degree of latitude for which the instrument is set.

That end, *r*, of the plate F in which the end of the central equator *o* *o* is always above the wire, *n*, (unless the instrument is set for one of the poles) is called the noon-arc, because it is actually a part of that meridian over which the sun stands while it is noon at the place where the observation is taken.

The object of the hour-lines (one to twelve) is to show at what time, for each place on the different degrees of latitude, the sun rises and sets.

Each line, designating a degree of latitude, on the plate F, is, by the hour-lines, divided into twelve equal parts, which indicate, with the imagined twelve equal parts on the opposite side of the plate F, the twenty-four hours, as aforesaid.

The lines on the opposite side of the plate would fall directly upon those on the front, and, therefore, those of the front have been marked with double rows of figures, in opposite directions.

Those figures marked from one to twelve, from the noon-arc *r* to the night-arc, are the figures for the face, while those from twelve to one are for the back of the plate F.

If the apparatus is set for the equator, the line *n* will cover the hour-line 6-6, and will thereby show that, at the equator, the sun rises and sets, on each day during the whole year, at six o'clock.

But this will at once be charged, as soon as the apparatus is shifted even for but one degree.

This invention will be of great value in schools, as all the important principles arising from the relative position and movements of the sun and earth can be easily explained and proved by its use.

The plate E will do the same service on land as an octant on sea, and even nautical students will profit much by studying this instrument.

The plates E and F are secured to the cube C by means of brackets *s* *s*, as shown, or otherwise, so as to turn, with the cube, around the axle B.

t *t* is a series of thumb-screws, arranged in the frame A, through the arc *c*, on the west side of the apparatus, to clamp the plate F, and, with it, the cube C and plate E, and their respective appendages, in any one desired position, after the apparatus has once been adjusted for a certain latitude.

G is a drawer or shelf, arranged within the cube C, for holding direction-book, instruments, &c.

I claim as new, and desire to secure by Letters Patent—

1. A heliometer, constructed and arranged to operate in the manner herein shown and described.

2. The arrangement of the northern and southern polar surfaces on opposite sides of the revolving cube C, substantially as herein shown and described.

3. The revolving dial-plates *h*, when arranged within the stationary dial-plates *d* and *e*, and when arranged within the circle on which the degrees of longitude are marked, substantially as and for the purpose herein shown and described.

4. The semi-cylindrical sun-dial D, when arranged as set forth, and when provided with a gnomon, *i*, substantially as and for the purpose herein shown and described.

5. The semi-cylindrical sun-dial D, when arranged as set forth, in combination with the double polar surfaces of the revolving cube C, upon which the dials for the northern and southern hemispheres are respectively arranged, substantially as and for the purpose herein shown and described.

6. The triangular plate E, provided with a hand or pointer, *K*, when connected with the revolving cube, and when combined with the semi-annular arc *o*, substantially as and for the purpose herein shown and described.

7. The flange around the plate E, when provided with a hole at m , for a ray of light to fall upon the opposite arcs, substantially as and for the purpose herein shown and described.
8. The curved block l , when attached to the revolving plate E, and when combined with the arc e , and when graduated, substantially as and for the purpose herein shown and described.
9. The plate F, when arranged in combination with the cube C and arc e , all made and operating substantially as herein shown and described.
10. The arrangement of the hour-lines, latitude-lines, and diagonal lines, on the plate F, as set forth.
11. The plate F, when arranged as set forth, and in combination with the stationary day-and-night divider n on the arc e , made as described.
12. The plate F, when arranged as described, in combination with the plate E and arcs e , and with the cube C, all made and operating substantially as herein shown and described.
13. The plates E and F, in combination with the sun-dials on the revolving cube C, made as described.

CONRAD FR. LUDV. RISCH.
